(57) **CLAIM**

I claim the ornamental design for a scooter frame with a wheel, as shown and described.

DESCRIPTION

FIG. 1 is a perspective view of a scooter frame with a wheel showing my present design;

FIG. 2 is a front view thereof;

FIG. 3 is a rear view thereof;

FIG. 4 is a left view thereof;

FIG. 5 is a right view thereof;

FIG. 6 is a top plan view thereof; and,

FIG. 7 is a bottom plan view.
